UNITED STATES PATENT OFFICE.

SAMUEL MALES, OF CINCINNATI, OHIO.

CIDER-MILL.

SPECIFICATION forming part of Reissued Letters Patent No. 9,508, dated December 21, 1880.

Original No. 52,583, dated February 13, 1866; Reissue No. 5,877, dated May 19, 1874; Reissue No. 6,504, dated June 22, 1875.
Application for reissue filed November 23, 1880.

To all whom it may concern:

Be it known that I, SAMUEL MALES, of Cincinnati, Hamilton county, Ohio, have invented certain new and useful Improvements in Cider-
5 Mills, of which the following is a specification.

My invention relates to an arrangement of intermeshing rollers whose crushing and feeding surfaces are so formed as to assist each other in feeding the apples and retaining the
10 broken pieces until effectually crushed between the segments thereof, with devices for feeding and breaking the apples.

Figure 1 is a perspective view of a cider-mill embodying my invention. Fig. 2 is a
15 transverse section of my rollers. Figs. 3 and 4 are an end view and section, respectively, of the gear-wheels, showing the chamfered bottom of the teeth.

A represents a customary inclosing-box, sur-
20 mounted by a suitable hopper, B, whose chute C conducts the apples between a corrugated throat, D, and a breaking and feeding roller, E. One end of the roller E is furnished with cogs F, which cogs gear into similar cogs F'
25 on one of the crushing-rollers, whose cogs also gear into similar cogs F" on the end of a pre-
cisely similar crushing-roller, H. The per-
iphery of each crushing-roller G and H is
30 composed of a number of cylindrical seg-
ments, I, armed along their middles with ribs
J, and separated from each other by grooves
K. Each rib J enters and sweeps around one
35 of the grooves K in the other roller, and each
rib J catches the broken pieces as they fall
from the roller E, and as it enters a groove,
K, in the other roller holds the piece between
the segments I, so that it (the piece of apple)
40 is necessarily crushed between the segments
and the cells thoroughly broken.

The rollers H and G, with their gear-wheels
F' and F", are cast or otherwise secured firmly
to their shafts in such a manner that at one or
more points, x, in the periphery of each roller

a rib or groove on the roller will be exactly in
line with a tooth or space in the gear-wheel. 45
In the drawings (see Fig. 2) four such points on
each roller agree in this way.

In putting the machine together it is sim-
ply necessary to bring one of these registering
points in the periphery of one roller opposite 50
one of the registering points in the opposite
roller, and the ribs and grooves will be found
to match properly in the motions of the roll-
ers, and thus the marking of the gear-wheels
before the machine is taken apart is obviated, 55
and there is no danger of getting the rollers
together out of proper relation.

The mill being started and apples being fed
into the hopper, the said apples are carried
down the chute C between the corrugated 60
throat D and feed-roller E, between which
they are broken into small pieces, and from
which they drop on rollers G and H, whose
ribs J catch and hold the fragments and
cause the segments of the coacting rollers to 65
crush all the cells of the pomace. At the
same time the ribs J act to strip the pomace
from the surfaces I and from the grooves K,
so as to preserve the full efficiency of these
parts at each succeeding revolution. 70

I claim—

1. In combination with a pair of crushing-
rollers having feeding and cleaning surfaces,
consisting of intermeshing ribs and grooves
and segmental spaces for crushing, a feeding 75
and breaking apparatus consisting of a cut-
ting-roller and corrugated throat, substantially
as and for the purpose set forth.

2. The crushing-rollers H G, provided with
cylindrical segments I, ribs J, and grooves K, 80
substantially as and for the purpose specified.

SAMUEL MALES.
